FOUNDATION GARMENT

Katherine K. Smythe, Evanston, Ill.

Application July 19, 1941, Serial No. 403,081

2 Claims. (Cl. 2-37)

This invention relates to wearing apparel and more particularly to a foundation garment and a method for the manufacture thereof.

One of the objects of the invention is to provide a foundation garment devoid of metal stays and other similar devices heretofore employed.

Other objects and advantages of the invention will be apparent from a reading of the following description in conjunction with the accompanying drawing, in which:

Figure 1 represents a front view of the new and improved type of foundation garment provided in accordance with this invention;

Figure 2 is a back view of the garment illustrated in Figure 1;

Figure 3 is a detail view of a combination thread which may be used in the practice of the invention; and

Figure 4 represents a fabric woven from the thread shown in Figure 3.

Referring to Figures 1 and 2, it will be seen that the garment illustrated comprises a back portion 2 jointed by means of seams 4 and 6 to side portions 8 and 10, respectively. The side portions 8 and 10 are in turn joined by means of seams 12 and 14 to other side panels 16 and 18 which in turn are joined by seams 20 and 22 to front panel portions 24 and 26. The upper panel portion 26 is joined by means of a seam 28 approximately at the waistline of the garment to the lower panel portion 24.

A feature of the present invention consists in the construction of the lower panel portion 24 of the garment from a stiff, thermoplastic resin in the form of a thread, preferably having a diameter from about .012 inch to about .050 inch woven into a fabric. The thread employed in making the lower panel portion 24 is substantially larger in diameter than ordinary thread and is relatively stiff as compared with ordinary thread, although still retaining a substantial amount of flexibility. The thermoplastic material employed for making the lower front panel portion 24 may be, for example, ethyl cellulose, or a basic thermoplastic resin of vinylidene chloride. One such resin is now made by the Dow Chemical Company under the trade name of "Saran." It has a tensile strength within the range of about 30,000 lbs. to 60,000 lbs. per square inch, a relatively high refractive index of about 1.63, can be flexed 250,000 times without fracture and is not affected by water, acids, alkalies, inorganic and most organic chemicals at moderate temperatures. A thread of this material having a diameter within the range from about .012

inch to about .050 inch is excellent for the purpose of the present invention. It will be understood, however, that other thermoplastic materials having similar properties may be employed. The thermoplastic material employed should be one which is flexible but which does not stretch substantially.

The upper front panel 26 of the garment shown in Figure 1 may be constructed of the same material as the lower panel 24, or it may be constructed of a combination of materials. One such combination, for example, which is preferably employed in accordance with this invention, involves the use of a thermoplastic thread of the same type as that employed for the lower panel 24, interwoven or knitted with transverse elastic threads of any conventional or well known type thereby permitting lateral contraction and expansion but without permitting vertical stretching of the garment. In another form of the invention the relatively stiff thermoplastic thread is made into a double thread by combining, twisting or interlocking it with an elastic thread. Thus, as shown in Figure 3, the thermoplastic thread 30 is combined with the elastic thread 32. The woven or knitted fabric made from this thread (Figure 4) is relatively stiff with some flexibility and substantial elasticity.

The side and back panels 2, 8, 10, 16 and 18 are preferably constructed of an expandable and contractible material of any well known type such as "Lastex." In certain instances it may be desirable to construct one or more of the panels 2, 8, 10, 16 and 18 from a substantially non-expandable and non-contractible material. Thus, as an example, the back panel 2 may be constructed of such a material while the side panels 8, 10, 16 and 18 are constructed of an elastic or expandable and contractible material.

The garment is preferably constructed in such a way that the rise above the waist level 28 is relatively small as compared with the lower portion of the garment below the waistline. The lower part of front panel 24 preferably gradually rises, or is higher in the central portion 34, thereof, as shown in Figure 1, while the back panel 2 drops below the average level of the bottom of the garment at point 36, as shown in Figure 2. In the upper panel 26 there is preferably a slight rise 38 centrally thereof and a drop in the back at point 40. The garment is preferably provided with elastic inserts 42 and 44, as shown in Figure 1. According to one preferred embodiment of the invention, the side and back panels 2, 8, 10, 16 and 18 are formed from

the expansible and contractible woven material shown in Figure 4. Instead of the usual double band around the bottom of a corset, the present invention also provides for a single band of stiff thermoplastic thread of the character herein described. It will be understood that the garment may be varied in size and shape.

The invention provides a comfortable garment. It eliminates the necessity of using stays or similar stiffening elements. The arrangement and construction shown makes it possible to eliminate the conventional band at the bottom of the garment. The invention also provides a garment which fits as high as a corselette but without straps.

Having thus described the invention, what I claim as new and desire to secure by Letters Patent of the United States is:

1. A stayless foundation garment of the character described comprising a plurality of front panel portions including a lower panel portion formed from a substantially stiff open mesh thermoplastic fabric capable of flexing without

stretching, and an upper panel portion adjacent said lower panel formed from a woven material having substantially stiff vertically extending threads and elastic transversely extending threads.

2. A stayless foundation garment of the character described comprising a plurality of panels extending in a generally vertical direction including a pair of side panels, a back panel and a front panel joined together to form a one-piece garment, said side panels being formed of an elastic material, said front panel being divided into an upper panel and a lower panel, said lower panel being formed from an open weave fabric in which the threads thereof are composed of a stiff thermoplastic substance having a diameter from about .012 inch to about .050 inch and said upper panel having vertically extending threads composed of the same thermoplastic material interwoven with transversely extending elastic threads.

KATHERINE K. SMYTHE.
